FLATIRON

Adolph Ronning, Minneapolis, Minn.

Application May 26, 1938, Serial No. 210,201

9 Claims. (Cl. 38—78)

This invention relates to improvements in flat-irons.

In the ironing or pressing of some goods, such as suits and the like, the work is not itself dampened but instead a dampened cloth is laid over the work, and the iron is then run over the cloth. There are a number of variations of this method of pressing, but all are predicated on the use, in some way, of a dampened cloth between the iron and the work, and all are relatively impractical in operation for the reason that the cloth is seldom evenly dampened and considerable time is required to periodically stop the work and dampen the cloth.

Having in mind these facts, it is the primary object of my invention to provide an iron, for this purpose, which has assembled thereon a cloth which is arranged to pass back and forth beneath the iron and which is automatically, continuously, and evenly dampened by dampening means on the iron. The iron, cloth, and dampening means thus operate as an integral unit, greatly speeding up the operation and assuring the user that the cloth will be properly dampened at all times.

Another object is to provide an electric flatiron assembly embodying a heated shoe member and handle, and with the pressing cloth arranged as an endless belt running lengthwise over and beneath the iron so that the lower reach or portion of the belt will be moved back and forth by contact with the work as the iron is moved over the work.

Another object is to provide in an iron as described, a dampening means which is effective by said movement of the cloth belt to dampen the same continuously and evenly so that, as the iron is moved either forwardly or rearwardly, a dampened stretch of the belt will be moved under the heated shoe to properly condition the goods being ironed and to prevent the goods from being scorched.

Another object is to provide an iron and dampening cloth assembly of this kind wherein the cloth is mounted over rollers arranged transversely at both front and rear ends of the iron, and which rollers are spring pressed in such manner as to maintain the cloth constantly in a taut condition beneath the iron and, further, to move the cloth away from the heated shoe when the iron is not in use. The latter action is especially necessary in order to prevent the cloth from being scorched, since the cloth is only dampened when the iron is in use and the cloth is in motion. The rollers are, therefore, spring mounted in such fashion that they will normally spring downwardly and elevate the heated shoe from the cloth, but the springs are, of course, only just sufficient to thus raise the shoe so that, when the hand is placed on the iron and the

iron put in motion, the shoe may be readily pressed to the work.

Another object is to provide an iron and pressing cloth apparatus of this kind in which the parts are assembled in a compact and integral form or unit, with a water chamber formed in the body member of the iron for carrying the water used to moisten the cloth, and with the chamber well insulated from the heated shoe of the iron to thus prevent the water from steaming off or evaporating too rapidly.

Another object is to provide, as a modification, an iron and pressing cloth assembly in which the cloth takes the form of a strip coiled at its ends around rollers carried by the iron and which rollers are spring set in such manner that they will maintain the cloth in a taut condition along the bottom of the iron, but will permit the cloth to work back and forth beneath the rim as it is reciprocated over the goods. Here again the rollers and spring set to normally elevate the iron out of contact with the cloth, as previously described.

A further object is to provide, in a modified assembly as above, means for dampening the cloth adjacent each end to thus insure that the cloth will be adequately and evenly dampened at all times.

Still a further object is to provide an assembly as described wherein the water is carried in small receptacles which are supported immediately over the rollers and arranged to feed the water into the cloth by means of depending wicks. This structure, of course, disposes the water containers well clear of the heated portions of the iron, and for this reason, as well as due to the use of two containers, the containers may be very small and compact.

The foregoing and other objects, together with means whereby the same may be carried into effect, will best be understood from the following detailed description, taken in connection with the accompanying drawings, wherein:

Fig. 1 is a side elevation, partially in section, of a preferred embodiment of my invention in which the cloth is arranged as an endless belt.

Fig. 2 is a plan view, with a part of the belt cut away and one roller shown partially exposed and in diametrical section.

Fig. 3 is a front end view.

Fig. 4 is a vertical cross section along the line 4—4 in Fig. 2.

Fig. 5 is a side elevation of a modified assembly in which the cloth is rolled at each end upon rollers and separate water containers are employed.

Fig. 6 is a fragmentary plan view of the frontal portion of the assembly shown in Fig. 5.

Fig. 7 is a similar plan view of a modified structure in which a single water chamber is used.

60

Fig. 8 is a side elevation, partially in section, showing the complete assembly employing a single water chamber as in Fig. 7.

Referring now with more particularity to the drawings, my invention as embodied in Fig. 1 through Fig. 4, comprises the body member A, the handle B, and the endless pressing or dampening cloth C. The body member A may be of any shape desired, and here is shown as having its frontal end 10 tapering to a point from its relatively wide rear or butt end 11. The body member, whatever its shape, includes as its base member the bottom sole plate or shoe 12, provided with a smooth and flat lower working face 13. Mounted atop this shoe 12 is the housing member 14 which is held in place by screws 15 and, in this case, this housing member is hollowed out medially to provide a water chamber 16 separated from the shoe 12 by the intervening bottom wall 17 of the housing. The water chamber is further insulated and isolated from the shoe 12 by a layer 18 of heat insulation so that heat from the shoe will be prevented, at least to a large extent, from reaching the water and causing it to evaporate too quickly. The chamber 16 may be filled through an opening 19 which is formed out to one side of the housing member 14. A bracket 20 is also extended from this side of the housing and is turned inwardly to support the handle B centrally over the iron, and this arrangement, as will be readily evident, leaves the entire upper surface of the iron clear of any projecting parts whatever.

A conventional electrical heating unit 21 is arranged in the shoe 12 and is connected by wires 22 to a switch 23 and plug receptacle 24 so that current may be carried through the usual cord and plug 25 to the heating unit under control of the switch. This switch may be of any conventional type, and the usual automatic heat control may also be used, if desired.

The dampening cloth C is, as stated, in the form of an endless cloth belt device and is supported on front and rear rollers 26 and 27 axised transversely with respect to the iron A. These rollers each comprise several units or separate pieces, and are journaled on axles 28 which are supported in the eyes 29 of spring arms 30 and 31 extended toward, and engaged with, the front and rear ends respectively of the housing member 14. The frontal arms 30 are inserted at their rear ends into bores 32 formed in the housing member (isolated from chamber 16) and are locked in any endwise adjusted position by the set screws 33. The rear arms 31 are slidably inserted at their frontal ends through plugs 34 which are screwed into recesses 35 formed in the rear end of the housing member 14 (also isolated from the chamber 16), and the ends of these arms have heads 36 which bear against expansion coil springs 37 placed in the recesses as shown. These springs 37 thus serve to normally urge the arms 31 rearwardly, increasing the distance between the rollers 26 and 27 to maintain the cloth belt C in a taut condition. Adjustments of the position of the frontal arms 30 may be made by means of the set screws 33 to thus adjust the spring tension on the cloth.

The rollers 26 and 27 are thus so positioned and supported in front of, and behind, the iron A that the cloth belt C will enclose the upper and lower sides of the iron. One reach or portion 38 of the belt thus passes over the top of the iron, and the other, 39, passes beneath the flat working face 13 of the shoe 12, and the width

of the belt is slightly greater than that of the iron to fully cover the iron as shown.

A slot 40 is cut transversely in the upper side of the housing member 14 in communication with the water chamber 16, and a dampening roller 41 is journaled on a transversely extended axle 42 in the chamber so that the upper arcuate portion of the periphery of the roller will project through the slot. The roller and slot are located just forwardly of the handle bracket 20, at substantially a medial point of the upper reach 38 of the cloth C, and the cloth is pressed downwardly against the exposed periphery of the roller 41 by an idler roller 43 which is disposed above the cloth and is urged downwardly by arms 44. These arms 44 are anchored at 45 in transversely extended studs 46 fixed to the bracket 20, and at their forward ends are formed into eyes 47 which receive the axle 48 of the roller 43. The arms 44 are furthermore formed of spring material and are tensioned to normally urge the roller 43 downwardly against the cloth C.

In operation, the iron is moved back and forth over the goods or the work in the usual manner, but this action, in addition to exerting a pressing force and effect on the work, also causes a frictional engagement between the cloth C and the work. This results in a reciprocating motion of the lower portion 39 of the cloth C, causing it to roll back and forth over the rollers 26 and 27 and, depending on the length of the stroke of the iron, causing the cloth to make one or more complete revolutions around the rollers, as will be understood. As the cloth moves it rotates the dampening roller 41, and this roller, operating in the water chamber 16, picks up water therefrom and applies it evenly and continually to the cloth as it moves. No matter in which direction the iron is moved, therefore, the moistened portions of the cloth will be constantly moved under the shoe 12 and between that shoe and the work so that the proper pressing effect is obtained without any attention on the part of the operator.

While the iron is in use the cloth C is, of course, pressed against the working face of the shoe 12 but, when the iron is not in use and the cloth is not moving, it is necessary to move the cloth away from the shoe. Otherwise the cloth would be scorched very quickly since the cloth is actually only moistened when in motion. For this purpose I make the arms 30 and 31 out of spring material and tension them to normally urge the rollers 26 and 27 downwardly to the position shown in Fig. 1 in dotted lines. This action elevates the shoe 12 from the cloth as clearly shown, and the arms 30 and 31 are so proportioned, and are of such strength, that they will just raise the iron when the hand is removed and then, when the handle B is grasped, the iron may be readily pressed to the work.

In order to keep the cloth C from working laterally off the rollers 26 and 27 I may make either or both of the rollers of the bulged shape shown in Fig. 2 with their center portions larger in diameter than the ends, to achieve a well known effect.

In the modification of my invention as shown in Figs. 5 through 8, the cloth C' is in the form of an elongated strip rolled or coiled at its ends around rollers 26 and 27 so that the free stretch 70 or reach 39a of the strip passes beneath the working face of the shoe 12. By this arrangement the top of the iron may be clear for the usual mounting of the handle B' from the bracket 20. The rollers 26 and 27 are, in this case, each 75

provided with a well known form of spiral spring, as indicated at 49 in Fig. 8, to keep the cloth stretched tautly across the shoe 12 but to permit the cloth to roll up on one roller while it unrolls from the other in the back and forth movements of the iron.

The rollers 26 and 27 are supported from the housing member 14 of the iron by carrier arms 50 and 51 which are pivotally mounted at 52 alongside the front and rear ends, respectively, of the member 14. The frontal arms 50 extend forwardly and carry the axle 28 of the roller 26 while the rear arms 51 extend rearwardly and similarly carry the axle 28 of the rear roller 27. Torsional coil springs 53 are coiled around the screws which form the pivotal connections 52, and the opposite ends of these springs engage the arms 50 and 51 at 54 and are secured to studs 55 in the sides of the member 14 in such manner that the rollers 26 and 27 are normally urged downwardly to move the cloth C' away from the shoe 12 and elevate the iron, for the purpose hereinbefore set forth. This downward movement is limited by engagement of stop fingers 56, formed on the arms 50 and 51, with the studs 55, as will be clearly evident.

In Figs. 5 and 6 the arms 50 and 51 have upwardly turned ends or extensions 57 on their outer ends, and small water tanks or receptacles 58 are supported between these ends immediately over each roller 26 and 27 and parallel therewith. These tanks thus provide water chambers into which water may be introduced through the removable plugs 59, and the water is fed to the clock C' by wicks 60 which depend from the tanks (in communication with the interior thereof) and engage across the width of the cloth as wound on the rollers. The cloth is thus constantly dampened at each end and, as the cloth moves back and forth and unrolls and rerolls on the rollers, these dampened portions of the cloth will be moved beneath the iron.

In Figs. 7 and 8 the housing member 14 has the water chamber 16 formed therein, as previously described, and provided with the filler plug 61. Wicks 62 are immersed in the water in the chamber and extend outwardly and downwardly at each end therefrom (through suitable passages 63) to engage the cloth C' across its entire width between the rollers 26 and 27 and the shoe 12. In this case the cloth is dampened immediately adjacent the shoe, and the iron may be used with very short strokes.

It is understood that I may vary from the structure as herein described, provided that such variations fall within the scope of the appended claims. Having thus fully disclosed my invention, what I claim as new and desire to secure by Letters Patent is:

1. A flatiron assembly including a heated working face, a pressing cloth adapted to cover the working face, rollers movably supporting the cloth for reciprocating movement over the working face in response to frictional engagement with the work, the said rollers being yieldably supported for normally urging the cloth out of contact with the said working face, and means for moistening the cloth.

2. A flatiron comprising, a shoe member having a lower working face, a pressing cloth adapted to cover the working face of the shoe member, and yieldable means spacing the cloth from the

bottom of the working face of the shoe member and movably supported on the shoe member to normally elevate the same out of engagement with the cloth.

3. A flatiron comprising, a shoe member having a lower working face, a pressing cloth adapted to cover the working face of the shoe member, spring acting means supporting the cloth from the iron and movable downwardly to normally elevate the shoe member out of engagement with the cloth, and means for dampening the said cloth.

4. In combination with an iron, rollers supported horizontally at the front and rear ends of the iron, an endless cloth belt trained over 15 the rollers and stretched across the upper and lower faces of the iron for movement thereover in response to movement of the iron over the goods, the said rollers being yieldably urged apart for stretching the cloth belt in a taut condition, 20 and means to moisten the cloth belt.

5. In combination with a flatiron having a working face, spring arms extended endwise from the ends of the iron, rollers journaled on the arms, a cloth belt trained over the rollers, and 25 movably extended lengthwise over the working face of the iron, means for dampening the cloth belt, and the said arms being tensioned to normally move the said rollers downwardly to thereby elevate the working face of the iron clear of 30 the cloth belt.

6. In combination with a flatiron including a body member and pressing face, rollers supported at the ends of the body member, a cloth strip coiled at its ends on the rollers and passing 35 between the rollers beneath the pressing face of the iron for reciprocating movement thereon in response to frictional contact with the work, the said rollers being spring set to normally maintain the cloth strip in taut condition and to roll 40 the strip as it moves off the pressing face, and means for dampening the cloth strip.

7. The combination with a flatiron having a pressing face, of spring arms extended endwise from the iron and resiliently urged downwardly 45 at their free ends, rollers journaled transversely between the free ends of the arms, and a cloth belt trained over the roller and supported thereby across the pressing face of the arms.

8. The combination with a flatiron having a 50 pressing face, of spring arms extended endwise from the iron and resiliently urged downwardly at their free ends, rollers journaled transversely between the free ends of the arms, and a cloth belt trained over the rollers and supported there- 55 by across the pressing face of the iron, at least a part of the said arms being spring pressed to normally move endwise from the iron and thereby retain the belt in a taut condition between the rollers.

9. The combination with a flatiron including a pressing face, of carrier arms pivotally supported on the iron and extended endwise therefrom for vertical movement at their free front and rear ends, rollers journaled on the arms at 65 their free ends, a cloth belt trained over the rollers and across the pressing face of the iron, and spring means operatively associated with said iron and said arms and normally and yieldably urging the free ends of the arms in a downward 70 direction.

ADOLPH RONNING.
